Primary Examiner — Patricia Palasik(74) *Attorney, Agent, or Firm* — Avery N. Goldstein;
Blue Filament Law LLC(57) **CLAIM**

The ornamental design for a robot, as shown and described.

DESCRIPTION

FIG. 1 is a front view of a robot;

FIG. 2 is a rear view of the robot depicted in FIG. 1;

FIG. 3 is a left side view of the robot depicted in FIG. 2, where the corresponding right side view is a mirror image of that depicted in FIG. 3;

FIG. 4 is a top view of the robot depicted in FIG. 1; and, FIG. 5 is a bottom view of the robot depicted in FIG. 1, where dashed line portions are not considered part of the inventive design.

The broken lines in the drawings depict unclaimed environmental subject matter.

1 Claim, 2 Drawing Sheets(56)
